UNITED STATES PATENT OFFICE.

LESTER V. STONE AND LLOYD J. STONE, OF AUGUSTA, GEORGIA.

HOISTING DEVICE.

1,134,707.

Specification of Letters Patent.

Patented Apr. 6, 1915.

Application filed April 30, 1914. Serial No. 835,397.

To all whom it may concern:

Be it known that we, LESTER V. STONE and LLOYD J. STONE, citizens of the United States, residing at Augusta, in the county of Richmond and State of Georgia, have invented certain new and useful Improvements in Hoisting Devices, of which the following is a specification.

The present invention relates to improvements in hoisting devices, and particularly to the type of portable hoists.

The primary object of the invention is the provision of a hoisting device or hoist which is especially adapted for use in ware-houses where baled cotton is to be stored in piles, in loading and unloading wagons, and in places where the space for operating such an apparatus is limited. While the device is of course applicable for use in connection with commodities other than baled cotton, and in places other than cotton ware-houses, it will be understood however that both time and labor are saved in cotton ware-houses where my device is used. Where the bales of cotton are to be stacked or piled from four to seven bales high with the stacks or piles extending over the entire area of the warehouse floor, it is necessary that a portable, and adjustably extensible hoisting apparatus be provided, and the device of the present invention is designed to fill this requirement.

The invention consists in certain novel combinations and arrangements of parts whereby the portable and adjustably extensible hoist is constructed and operated as will be clearly pointed out hereinafter and more particularly set forth in the appended claims.

In the accompanying drawings one complete example of the physical embodiment of the invention is illustrated as constructed according to the best mode so far devised for the practical application of the principles of the invention, but it will of course be understood that changes and alterations may be made in the apparatus within the scope of the following claims without departing from the spirit of the invention.

Figure 1 is a perspective view of the device complete, built according to this invention. Fig. 2 is an enlarged, vertical sectional view of the device, with some parts omitted for convenience of illustration. Fig. 3 is a detail transverse sectional view on line 3—3 of Fig. 2.

In the preferred embodiment of the invention as illustrated in the drawings a wooden platform or base 1 is employed from which the apparatus is supported. This base is provided with shoes or bars 2, 2, from which the sharpened steel spikes 3, 3, project under the base and these spikes are designed to enter the floor of the warehouse and form an anchorage for the hoist and hold it stable and steady while the device is in use.

Upon the base or platform 1 a tubular standard or hollow post 4, preferably of cast metal, is fixed, and this standard is designed to guide and support the vertically adjustable and rotary movable crane which comprises a straight vertically arranged post 5 formed with an arch or bend 6 at its top and composed of piping or tubing to provide strength and lightness, and also for the accommodation of the hoisting rope 7 which passes therethrough. Across the arc of the arch 6 a brace bar or bars 8' are arranged, their ends being fixed to the tubing of the arch and post, and a pulley 8 and 9 at the respective ends of the bars are provided to guide and support the hoisting rope 7 which passes up through the post and over the pulleys 8 and 9, and has attached at its free end the bale hooks and chains 10 as usual.

The crane is vertically movable and adjustable, in order to adapt it for use in varying heights of piles or stacks of bales, so that as the height of the stack increases the altitude of the crane may be increased. For this purpose a raising or lifting device is associated with the tubular standard and the hollow crane, including a rigid supporting tube or pipe 11 fixed to the platform and also rigidly attached to the tubular standard by metallic straps or bands 12, 13 which extend around the standard and tube and rigidly brace the parts together.

In the upper strap or band 13 a rack wheel 14 is journaled on its shaft 15, and in Fig. 100 2 it will clearly be seen that the wheel is located between the standard and tube and is in mesh with the teeth of a rack bar 16 which is shown as emerging from the tube 11. This rack bar is adapted to move vertically within the tube 11, and at its upper end is attached rigidly to the angle bracket 17 which is fashioned with a sleeve 18 that is slidable on the post 5 of the crane. At the upper and lower sides or top and bottom of this sleeve a pair of adjustable collars 19 and 20 are located, each of which

has a set screw or bolt 21 by means of which the collars may be fixed on the post. Thus by means of the collars the rack bar may be adjusted with reference to the crane, and 5 fixed in adjusted position with quickness and dispatch. The shaft 15 and wheel 14 are turned through the medium of a pair of sprocket wheels 22 and 23, the former on the shaft 15 and the latter on a shaft or post 10 24 in the band 12. A sprocket chain connects these wheels, designated by the number 25, and a crank handle 26 may be utilized to turn the two wheels and chain, and through them the rack wheel to lift or permit the lowering of the rack bar. Any suitable locking devices may be provided to hold the parts when desired. At the junction of the arch with the post of the crane, 15 a wheel 27 is journaled in the bracket 28 fixed to the crane, for a purpose to be described.

In addition to the vertical adjustment of the crane, it is also capable of rotary motion and to attain this motion an adjustable 25 ring 28' is utilized. This ring is slideable on the post of the crane and may be secured at a predetermined point by means of the set screw or bolt 29. Thus in Fig. 2 the ring has been fixed to support the crane at 30 its minimum height, and the ring is resting on a supporting head 30 at the upper end of the tubular standard. To facilitate the free movement of the crane in revolving or rotating, a pair of ball bearings are provided, an upper bearing being indicated at 35 31 as carried by the tubular standard, and a lower bearing 32 being fixed at the lower end of the crane post, and in this manner the crane may swing throughout a complete 40 circle, it being understood that the post turns freely in the sleeve 18 before described.

The raising and lowering of the load of the crane may be accomplished by either 45 an electric motor 33 or a manually operated crank 34, as desired. In Fig. 1 the crank 34 is represented as tied by a chain 35 and manual labor in lifting is dispensed with, while the motor is used, but when the crank 50 is used the shaft 36 is revolved by means of the two gears 37 and 38, as will be readily understood.

The shaft is supported between two side plates 39 preferably of metal that are fixed 55 to a wooden frame 40 supported on the platform 1, and it will be noted that the motor is also supported on the frame. The shaft 36 supports the winding drum 41 and it is revolved from the motor through the medium 60 of the belt 42 and drive wheel 43 as will be evident from an inspection of Fig. 2, a friction wheel 44 and lever 45 being employed in connection with the belt to regulate the tractive power of the belt on the 65 wheel.

The cord or cable 7 passes from the drum to the tubular standard and post and is guided by means of a pulley 46 journaled in the side plates 39 of the frame 40, and in raising or lowering the bale of cotton 47 70 any suitable reversing or holding devices may be employed to permit the free running of the rope or cable when desired.

The hoisting device is braced and supported by means of the stay bars or rods 48 75 which have pointed ends to engage the floor and are loosely attached to the head 30 of the tubular standard, and in addition to these bars, a second pair of connecting bars 49 are used to connect the standard with 80 the frame 40, so that the entire hoisting apparatus is well and evenly braced against strains.

To insure the successful accomplishment of work with a hoisting device in a cotton 85 warehouse, it is highly desirable and essential that the device be portable and easily carried about from one point of operation to another. In this respect the hoist fulfills its function completely, as the hoist may be 90 moved about on its wheels 50 by means of the barrow-handles 51 which are fixed to the frame 40. When it is desired to transfer the hoist from one location to another the wheels 50 are turned down to contact 95 with the floor, and then the hoist is moved like a wheel barrow. But when it is desired to move the hoist any considerable distance, or if the hoist is too heavy for use similar to a barrow, the wheel 27 is used in connection with the wheels 50 to support the entire device. These wheels 50 are each journaled at 52 in an angle bracket 53 which is rigid at the ends of the cross or rock bar 54 revoluble in the ears or bearing lugs 55 105 fixed at the front of the platform 1. A crank shaft 56 movable in its bearings 57 is located parallel with the rock bar and this crank shaft is connected to the angle brackets by means of a pair of draw links 110 58, while a connecting link 59 pivoted on the crank shaft connects it with a pivoted actuating lever 60 pivoted at 61 on the platform. By means of a wire loop 62 the lever may be locked in position. Thus when 115 it is desired to bring the wheels 50 in contact with the floor, the lever is pulled to the left in Fig. 2 and through the described connections the wheels are thrown down so that the entire device may be supported on 120 the two wheels when it is lifted by the barrow handles. When it is desired to support the device on three wheels for transportation, the crane is revolved or swung around to the left in Fig. 1 so that the wheel 125 27 is in line with the wheels 50, and after these latter wheels are turned down the hoist may be tipped or tilted over to the right in Fig. 1 to rest on the three wheels.

In actual practice it has been found that 130

the device is facile in operation, efficient, and economical in time and labor expended in stacking or piling cotton bales or other commodities, and in many other ways possesses meritorious characteristics which recommend it for extensive use.

Having thus fully described the invention, what is claimed and desired to be secured by Letters Patent is:—

10 1. The combination with a tubular standard of a crane having a post telescoping therewith, a rack bar having a sleeve slideable on said post, adjustable collars for fixing said sleeve, and an adjustable supporting ring on the post for the purpose described.

20 2. The combination with a tubular standard of a crane having a post telescoping therewith, a rack bar and a tubular guiding member therefor, a rack wheel engaging the bar and actuating means therefor, a fixed sleeve on the bar slidably connected with the post, adjustable collars for fixing the sleeve on the post, and an adjustable supporting ring on the post for the purpose described.

25 3. In a hoist the combination of a platform, a tubular standard mounted thereon, a crane having its vertical portion fitting and adjustable in said standard, a hoisting rope guided in said crane, a bale hook secured to one end of said rope, a drum for winding said rope, a vertical tube mounted on the platform, a band connecting the tu-

bular standard and vertical tube, a pinion 35 mounted in said ring, a rack bar connected to said crane and fitting in the tube and meshing with said pinion, and sprocket wheels and chain for revolving said pinion to raise and lower said rack.

4. In a hoist, the combination of a platform, a tubular standard thereon, a tubular crane, consisting of an arched and vertical portion mounted in said standard, a hoisting rope passing through the vertical portion of said crane, guide pulleys for said rope mounted in the bend of the crane, a chain and bale hooks secured to the free end of said rope, a hoisting drum for the rope mounted on the platform, a vertical 50 tube rising from the platform parallel to said tubular standard, a rack rod guided in said tube and connected with the crane, a pair of bands connecting the standard and tube, a pair of shafts mounted in said bands, 55 sprocket wheels on said shafts, a sprocket chain connecting said wheels, a crank on the lower of said shafts, and a pinion on the upper shaft meshing with the rack bar for raising and lowering the bar and crane. 60

In testimony whereof we affix our signatures in presence of two witnesses.
